BELT

Moses Halio, 15 Voorhis Ave., Rockville Center, N.Y.

Filed July 8, 1960, Ser. No. 61,277

Term of patent 3½ years

(Cl. D3—10)

The figure on the drawing is a front perspective view of a belt showing my new design as it appears with parts thereof broken away to indicate indefinite length.

I claim:

The ornamental design for a belt, substantially as shown and described.
